(57) **CLAIM**

The ornamental design for a medical syringe, as shown and described.

DESCRIPTION

FIG. 1 is a front, top, and right side perspective view of a medical syringe showing our new design;

FIG. 2 rear, bottom, and left side perspective view thereof;

FIG. 3 is a front view thereof;

FIG. 4 is a top view thereof;

FIG. 5 is a right side view thereof;

FIG. 6 is a left side view thereof;

FIG. 7 is an enlarged view of the circumscribed area 7 in FIG. 3; and,

FIG. 8 is a cross-sectional view taken along line 8-8 of FIG. 7.

The evenly spaced broken lines in the figures show portions of the medical syringe that form no part of the claimed design. The dot-dashed broken lines depict the bounds of the claim and form no part thereof. The dot-dot-dashed broken lines circumscribe the enlarged views and form no part of the claimed design.
